(57) **CLAIM**

The ornamental design for a tray for coffee capsules, as shown and described.

DESCRIPTION

FIG. 1 is a top perspective view of a tray for coffee capsules showing my new design;

FIG. 2 is a front view thereof;

FIG. 3 is a rear view thereof;

FIG. 4 is a left side view thereof;

(Continued)

FIG. 5 is a right side view thereof;
 FIG. 6 is a top view thereof; and,
 FIG. 7 is a bottom perspective view thereof.
 The broken lines depict portions of the tray for coffee
 capsules that form no part of the claimed design.

1 Claim, 7 Drawing Sheets
